United States Patent

Des. 241,836

Patented Oct. 12, 1976

241,836

RECEIVER AND STOCK OF SHOTGUN

William B. Ruger, Southport, and Lawrence L. Larson,
Bethany, Conn., assignors to Sturm, Ruger & Co. Inc.,
Southport, Conn.

Continuation-in-part of abandoned design application Ser.
No. 521,879, Nov. 7, 1974. This application July 8,
1975, Ser. No. 594,101

Term of patent 14 years

Int. Cl. D22—05

U.S. Cl. D22—6

FIG. 1

FIG.2

FIG.3

FIG. 1 is a perspective view of the right-hand side of a receiver and stock of a shotgun;

FIG. 2 is a perspective view of the left-hand side of the receiver and the adjacent portion of the stock of the shotgun shown in FIG. 1;

FIG. 3 is a top plan view of the receiver and adjacent portion of the stock of the shotgun shown in FIG. 1;

FIG. 4 is a left-hand side elevation of the receiver and the adjacent portion of the stock of the shotgun shown in FIG. 1, the right-hand side thereof being a mirror image of the left-hand side; and

FIG. 5 is a bottom plan view of the receiver and the adjacent portion of the stock of the shotgun shown in FIG. 1.

The broken lines are for illustrative purposes only.

This application is a continuation-in-part of co-pending application for a patent for a design Ser. No. 521,879, filed Nov. 7, 1974, now abandoned.

We claim:

The ornamental design for a receiver and stock of shotgun, substantially as shown and described.
